Patented Aug. 14, 1923.

UNITED STATES PATENT OFFICE.

CLIFFORD J. CROSS, OF NEW YORK, N. Y.

STOPPER.

Application filed November 11, 1920. Serial No. 423,457.

To all whom it may concern:

Be it known that I, CLIFFORD J. CROSS, a citizen of the United States, and a resident of the city of New York, borough of Manhattan, in the county of New York and State of New York, have invented a new and Improved Stopper, of which the following is a full, clear, and exact description.

This invention relates to improvements in stoppers, and more particularly to stoppers for bottles or other containers for fire extinguisher, an object of the invention being to so construct the stopper as to insure its withdrawal from the bottle or container when the stopper is held and the bottle or container moved away from the same.

Heretofore, in supporting containers for fire extinguisher, it has been common practice to provide an eye on the stopper which is connected to a fixed part so that when a pull is had on the container, the stopper is removed from the bottle so that the contents of the container can be instantly scattered about. The eyes of such stoppers have been ordinarily connected to the stopper by means of a corkscrew and frequently these corkscrews pull out of the stoppers so that the stopper is not withdrawn from the bottle or container. This is particularly true after the stopper becomes dry from age.

It is the purpose of my invention to construct a stopper so as to insure the removal of the stopper by means of a pull on the bottle or container and to permit a certain amount of adjustment of the stopper transversely to insure a tight fit in the neck of the bottle or container.

With these and other objects in view the invention consists in certain novel features of construction, and combinations and arrangements of parts, as will be more fully hereinafter described and pointed out in the claims.

In the accompanying drawings—

Figure 1 is a perspective view illustrating one form of my invention.

Figure 2 is a view in longitudinal section showing the stopper in the neck of a bottle.

Figure 3 is a perspective view similar to Figure 1 illustrating a modification.

Figures 4—5, 6—7, and 8—9 are views illustrating other modifications.

Referring particularly to Figures 1 and 2, 55 1 represents my improved stopper which is preferably of cork, although it may be made

of any other suitable material, and which is preferably of slightly conical or tapering form to fit within the neck 2 of a bottle or container 3.

The stopper 1 is provided centrally with a longitudinal opening 4 to receive a screw 5 and I would have it understood that I preferably provide the opening 4 of less diameter than the diameter of the screw so that the teeth of the screw bite into the walls of the opening. A washer 6 is interposed between the head 7 of screw 5 and the lower end of the stopper 1 and a similar washer 8 is provided on the screw at the upper end of the stopper.

On the upper end of the screw 5 I secure a bail 24 by means of a nut 25. This bail 24 is preferably formed of a strip of sheet metal bent into general oblong shape with its perforated ends 26 overlapping and receiving the end of the screw 5 and the nut 25, which is angular in form, fits snugly between the side members of the bail 24 and screws onto the screw 5, so that the bail 24 operates as a wrench to turn the nut and adjust the same on the screw as may be desired.

In the modification illustrated in Figure 3 I provide a nut 9 of cylindrical form on the upper end of the screw 5, said nut having 85 sockets 10 in its opposite sides receiving the inwardly bent ends 11 of a wire bail 12. The upper end of the screw 5 is perforated, as shown at 13, for the reception of a cotter pin 14 to prevent possibility of accidental removal of the nut 9.

The bail 12 serves the double purpose of a connecting medium to connect the stopper with a fixed support in any approved manner, and also operates as a finger hold to 95 permit the nut to be turned on the screw.

When the nut is screwed home, it operates to draw the washers 6 and 8 toward each other, and this movement of the washers compresses the stopper 1 longitudinally and expands it transversely so that an adjustment can be had to insure the desired fit in the neck of the bottle. A pull on the bail 12 will insure the removal of the stopper from the bottle as, by reason of the arrangements of parts above described, there can be no possibility of the accidental removal of the bail without removing the stopper with it.

In the modified form of nut illustrated in Figures 4 and 5, the bail portion 14 is made integral with a nut 15.

In the modification illustrated in Figures 6 and 7, I illustrate a metal strip 20 which is perforated at its intermediate portion 21 to receive the screw 5, and a nut 22 is screwed onto the screw 5 and against the intermediate portion 21 of the strip. The ends of the strip are then curved upwardly and secured together by means of a rivet 23 or other securing device so that the strip 20 constitutes a bail for the same purpose as the bail 12 of the preferred form. It is, of course, to be understood that the strip 20 is shaped, as shown in Figure 7, before insertion on the screw 5 so that the parts can be quickly assembled or taken apart as may be desired.

In the modification illustrated in Figures 8 and 9, the bail 16 has its ends projected through and secured in openings 17 in the wings 18 of a nut 19.

Various other slight changes might be made in the general form and arrangement of parts described without departing from the invention, and hence I do not limit myself to the precise details set forth, but consider myself at liberty to make such changes and alterations as fairly fall within the spirit and scope of the appended claims.

I claim:

30. 1. A device of the character stated comprising a stopper, a screw mounted in and having its outer end projecting through the

stopper, a bail loosely mounted on the outer end of the screw and having a portion surrounding the stem of the screw, a nut on the screw, and lateral side portions of the bail member disposed on opposite sides of the nut which fits snugly therebetween.

2. A device of the character stated, comprising a stopper having a central opening, 40 a headed screw in the opening of the stopper, washers on the screw at opposite ends of the stopper, a bail having flat members and loosely mount on the screw, and an angular nut on the screw within the bail 45 and engaging the members of the bail.

3. A device of the character stated, comprising a stopper having a central opening, 50 a headed screw located in and engaging the walls of said opening, washers on the respective ends of the screw located against the ends of the stopper, a bail having perforated overlapping ends receiving one end of the screw, and a nut fitting within the bail and engaging the end of the screw. 55

4. A device of the character stated, comprising a stopper, a screw extending longitudinally through the stopper, a bail comprising a strip of metal having overlapping perforated ends receiving one end of the 60 screw, and an angular nut fitting between the side members of the bail and having threaded engagement with the screw.

CLIFFORD J. CROSS.
